UNITED STATES PATENT OFFICE.

BENEDICT E. WILLETT, OF MONTGOMERY COUNTY, NEAR DAYTON, OHIO.

DESIGN FOR A DISPLAY-RACK.

54,883.

Specification for Design.

Patented Apr. 13, 1920.

Application filed June 7, 1919. Serial No. 302,604. Term of patent 14 years.

To all whom it may concern:

Be it known that I, BENEDICT E. WILLETT, a citizen of the United States, residing in the county of Montgomery, near the city of Dayton, State of Ohio, have invented a new, original, and ornamental Design for a Display-Rack, of which the following is a specification, reference being had to the accompanying drawings, forming part hereof.

Figure 1 is a side elevational view of a display rack showing my new design. And Fig. 2 is an end view thereof.

I claim:

The ornamental design for a display rack, as shown.

BENEDICT E. WILLETT.

Witness:

HOWARD S. SMITH.
